Primary Examiner — Adir Aronovich*Assistant Examiner* — Ramzi Almatrahi*(74) Attorney, Agent, or Firm* — Fish & Richardson P.C.(57) **CLAIM**

The ornamental design for a charging connector for an automobile, as shown and described.

DESCRIPTION

FIG. 1 is a front perspective view of a charging connector for an automobile showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a reduced perspective view showing the status in which the lid is opened; and,

FIG. 9 is a left side elevational view showing the status in which the lid is opened.

The features shown in broken lines in the drawings depict environmental subject matter only and form no part of the claimed design.
